(57) **CLAIM**

The ornamental design for a video camera, as shown and described.

DESCRIPTION

FIG. 1 is a front perspective view of a video camera, showing our new design;

FIG. 2 is a rear perspective view thereof;

FIG. 3 is a front elevation view thereof;

FIG. 4 is a rear elevation view thereof;

FIG. 5 is a left side elevation view thereof;

FIG. 6 is a right side elevation view thereof;

FIG. 7 is a top plan view thereof;

FIG. 8 is a bottom plan view thereof;

FIG. 9 is a front perspective view thereof, shown with the video camera in an alternate position, with the middle section pivoted in an alternate position; and,

FIG. 10 is a front perspective view thereof, shown with the video camera in a second alternate position, with the middle section pivoted in a second alternate position.

The broken lines in the drawings illustrate portions of the video camera which form no part of the claimed design.

1 Claim, 10 Drawing Sheets
